CLAIM

The ornamental design for a hood for vehicle, as shown and described.

DESCRIPTION

FIG. 1 is a front perspective view of a hood for vehicle showing our new design;

FIG. 2 is a front view thereof;

FIG. 3 is a rear view thereof;

FIG. 4 is a left side view thereof, the right side view being a mirror image of the left side view;

FIG. 5 is a top view thereof; and,

FIG. 6 is a bottom view thereof.

It will be understood that the broken lines shown in the drawings illustrate portions of the hood for vehicle that form no part of claimed design.

1 Claim, 5 Drawing Sheets
